Patented June 2, 1925.

UNITED STATES PATENT OFFICE.

WILLIAM SEVERNS, OF CHICAGO, ILLINOIS.

FOUNTAIN BRUSH.

Application filed July 15, 1922. Serial No. 575,321.

To all whom it may concern:

Be it known that I, WILLIAM SEVERNS, a citizen of the United States, and a resident of the city of Chicago, in the county of Cook and State of Illinois, have invented certain new and useful Improvements in a Fountain Brush; and I do hereby declare that the following is a full, clear, and exact description of the same, reference being had to the accompanying drawings, and to the numerals of reference marked thereon, which form a part of this specification.

This invention relates to a fountain brush adapted for receiving a fluid under pressure interiorly thereof.

The invention concerns itself with a brush consisting of a pair of parallel portions or branches in spaced relation in combination with a nozzle located between said parallel portions and so constructed and secured that the spraying fluid will be directed into the parallel branches.

The invention comprises the novel mechanism and combinations hereinafter described and more particularly pointed out and defined in the appended claims.

In the accompanying drawings, which illustrate a preferred embodiment of this invention, and in which similar reference numerals refer to similar features in the different views:

Figure 1 is an elevational view of the brush with the nozzle attached.

Figure 2 is a view similar to Figure 1 with parts shown in section.

Figure 3 is a section on the line 3—3 of Figure 1.

Figure 4 is a fragmentary plan view of the nozzle upon an enlarged scale.

Figure 5 is a section upon the line 5—5 of Figure 2 upon an enlarged scale.

Figure 6 is a section upon the line 6—6 of Figure 2 upon an enlarged scale.

Figure 7 is a detail sectional view taken centrally through the securing block on the handle, showing the means for alining the nozzle with respect to the brush.

As shown on the drawings:

In referring now to the drawings, which illustrate one embodiment of this invention, the numeral 1 represents a brush in which the bristles are secured or entwined upon a flexible support such as the double strands of wire 2 which are bent into an oblong shape providing a brush having two spaced parallel portions or branches joined by an

arcuate portion. The two branches of the brush are supported and maintained in spaced relation by means of a centrally apertured securing block 3 having suitably spaced apertures for receiving the ends of the wire 2, which may be clamped therein by means of the set screws 4 (Fig. 5). The securing block 3 is also provided in its front face with a socket for receiving a centrally bored handle 5. The inner end of the handle may also be provided with spaced apertures or sockets to receive the ends of the wires 2, precluding relative rotation between the block 3 and handle 4.

A nozzle 6 in the form of a hollow tube is supported between the parallel branches of the brush by means of the block 3 and handle 5 through the central apertures of which the nozzle 6 extends, the outer end of the nozzle being provided with screw threads or the like for receiving a nut or hose coupling 7 attached to a hose 8, and a nut 7^a may be threaded upon said threaded portion to retain the nozzle when the base is removed. The portion of the nozzle between the branches of the brush is perforated at 6¹ in a single diametrical plane, as shown in Figures 2 and 3, so that the water or fluid will only be sprayed therefrom in opposite directions directly into the opposed branches of the brush.

In order to retain the nozzle in its proper relation with the brush so that the plane of the perforations 6¹ thereof will pass through the central axes of the branches of the brush, an alining pin 9 is secured in the nozzle so that its two ends project slightly beyond the nozzle, as shown in Fig. 6, and alined grooves 9¹ are made in the inner face of the block 3 in diametrically opposite points of the central aperture to receive the ends of the pin, as shown in Figures 6 and 7, whereby relative rotation between the nozzle and brush is prevented. It will readily be apparent that the pin 9 lies at right angles to the plane of the perforations of the nozzle and the grooves 9¹ in the block lie in a plane at right angles to the plane passing through the center lines of the branches of the brush; hence the nozzle will be retained by the pin so that the diametrically opposite series of perforations 6¹ will lie in the plane passing through the axes of the two branches. It is, however, obvious that the pin 9 may have any angularity to the plane of the perforations if the alined grooves 9¹ have a corre-

sponding angularity. The inner end of the nozzle may be closed by a cap 10 fitting over the end thereof, or by a cap 10^a fitting interiorly thereof and of a diameter no greater than the nozzle so that there will be less liability of interference with the object upon which the brush is being used.

From the foregoing it will be apparent that the nozzle is so constructed and alined 10 that it will only spray water through diametrically opposite points which lie in a plane passing through both of the longitudinal axes of the branches of the brush so that a better saturation of the brush will 15 be maintained and the spray will be more effectively broken up or retarded.

I am aware that numerous details of construction may be varied through a wide range without departing from the principles 20 of this invention, and I therefore do not purpose limiting the patent granted otherwise than necessitated by the prior art.

I claim as my invention:

In a fountain brush, a pair of spaced parallel scrubbing elements, a nozzle disposed therebetween having perforations directed only toward said scrubbing elements, a pin extending through said nozzle, a supporting block for the brush having an aperture for receiving said nozzle, said block 25 having alined grooves on opposite sides of said aperture for receiving said pin to hold said nozzle in proper position with its perforations directed toward said scrubbing elements, and a hollow handle secured to 30 said block for receiving the outer portion of said nozzle interiorly thereof.

In testimony whereof I have hereunto subscribed my name in the presence of two subscribing witnesses.

WILLIAM SEVERN.
